Attorney

UNITED STATES PATENT OFFICE.

FRANK C. SMITH, OF INDIANAPOLIS, INDIANA.

SASH-CORD POCKET.

Application filed December 4, 1924. Serial No. 753,942.

My said invention consists in an improved construction of metal pocket for receiving and attaching the end of the cord for supporting a sash balance weight to a window sash in such a way that the attachment may be easily made without removing the sash from the window frame, all as will be hereinafter more fully described and claimed.

Referring to the accompanying drawings, which are made a part hereof and on which similar reference characters indicate similar parts,

Figure 1 is a perspective view of one corner of a window sash showing a weight cord attached thereto by means of my invention, and

Figure 2, a detail sectional view more clearly illustrating the construction of the metal pocket.

In said drawings the portions marked A represent the window sash, B the cord, and G the pocket casing.

The sash A and cord B are of any usual or approved construction and need no special description. The sash A has a groove a along the edges extending from the top thereof to the pocket C.

The pocket consists of a metal casing C, preferably a section of malleable tubing, mounted in an angular aperture in the sash, the aperture being bored on an angle as shown with its outer end at a distance from the edge of the sash and the angle being such as to intersect the groove a, as shown most clearly in Figure 2. The tube C has a perforation c in its upper side in line with the groove a in the sash and its inner end is cut so that a lip 10 extends out therefrom on its short side which is bent over on an angle parallel with the edge of the sash and thus practically closes the inner end of the pocket and also protects the cord from frictional contact with the frame and consequent undue wear, all as most clearly shown in Figure 2.

The outer end of tube C is cut at an angle to parallel the face of the sash when in place and when in position is slightly inside said face.

A cap or cover 11 is provided to close the outer end of the pocket. It is formed with a lip 12 adapted to engage in a notch or slot 13 cut in the upper side of the tube C closely

adjacent to the outer end thereof and has a depending ear 14 with a perforation 15 through which a wood screw 16 extends into the sash for securing said cap or cover in place.

In use the parts being arranged as indicated in the drawings and the sash being in position in the window frame the sash cord B will be inserted in the groove a from the top and its end will pass through the perforation c into the tube C which because of its angular position will guide the end of the cord to the outside when a knot 20 may be formed therein and the cord then drawn back into the tube as indicated by dotted lines in Figure 1, thus securing the cord to the sash. The cap 11 is then adjusted by inserting the upper end of lip 12 in the slot 13 and inserting screw 16 in position which secures said cap flush with the surface of the sash, which is thus hung in position and ready for operation, all as will be readily understood.

Having thus fully described my said invention, what I claim as new and desire to secure by Letters Patent is:

1. A sash cord pocket comprising a long straight sheet metal body of substantially uniform cross section mounted in the window sash and extending from one face angularly to another face and intersecting the groove therein said pocket having an opening adapted to register with said groove and having an extension at one end bent over and forming a closure for said end, substantially as set forth.

2. A sash cord pocket comprising an elongated body of substantially uniform cross section adapted to be mounted angularly in a window sash to extend from one side to the edge thereof, a cover for said pocket said body having a perforation for receiving a window cord at one end and having a perforation at its other end to receive a lip on the cover for the pocket, said cover having an extension opposite said lip for accommodating a fastening element, substantially as set forth.

In witness whereof, I have hereunto set my hand and seal at Indianapolis, Indiana, this 2nd day of December, A. D. nineteen hundred and twenty-four.

FRANK C. SMITH. [L. s.]
